CLAIM

I claim the ornamental design for a hair removal device, as shown and described.

DESCRIPTION

FIG. 1 is a perspective view of a hair removal device showing the new design;

FIG. 2 is a top side view thereof;

FIG. 3 is a bottom side view thereof;

FIG. 4 is a left side view thereof;

FIG. 5 is a right side view thereof;

FIG. 6 is a rear view thereof; and,

FIG. 7 is front view thereof.

In these drawings, the solid lines illustrate the claimed ornamental design. Broken lines, if present in the drawings, are for illustrative purposes only and form no part of the claimed design.

1 Claim, 3 Drawing Sheets(56)
